(57) CLAIM

The ornamental design for scrub pants, as shown and described.

DESCRIPTION

FIG. 1 is a front view of scrub pants showing the claimed design;

FIG. 2 is a rear view thereof;

FIG. 3 is a left side view thereof;

FIG. 4 is a right side view thereof; and,

FIG. 5 is a front perspective view thereof.

The dot-dash broken lines in the figures and the areas within the dot-dash broken lines show portions of the scrub pants that form no part of the claimed design.

The dashed broken lines show a stitching pattern. The dashed broken lines form part of the claimed design.

1 Claim, 5 Drawing Sheets
